UNITED STATES PATENT OFFICE.

WILLIAM HENRY OWEN, OF WIMBLEDON, ENGLAND.

AIR PREHEATER FOR FURNACES.

Application filed August 16, 1924, Serial No. 732,512, and in Great Britain September 3, 1923.

This invention has reference to the application of pre-heated air to furnaces. According to the invention the air pre-heater arrangement comprises two sections or air heaters, viz a preliminary heater and a final heater, with an economizer between them so arranged that the whole of the waste gases from the furnace traverse them successively or in series. Hence in effect one heater is nearer to the furnace than the other, and therefore being hotter forms a final or extra-heater for that portion of the air which passes through it.

The whole of the incoming air is caused to pass first through the preliminary heater, that is to say the one remote from the furnace, thus having its temperature partly raised. It is then divided into two parts or currents one part going direct into the furnace below the grate, that is into the ashpit. The other part is passed through the final and hotter heater, viz—that nearer to the furnace, thus having its temperature raised still higher (that is to say, becoming extra-heated) and being then led to the space above the furnace grate, where it mingles with and actively promotes the combustion of the fuel gases.

In the accompanying diagrammatic drawings;

Figs. 1 and 2 illustrate in side and front view, and partly in section on the lines $x-x$ and $y-y$, respectively, the application of the invention to a water-tube boiler having an ordinary chain-grate.

a is the outer casing or shell of the boiler, and b is the chain or other automatic grate which is arranged in the boiler furnace and is of any convenient type. c is the feed hopper and d represents the front wall of a closed ashpit arrangement. e is the ordinary heat-radiating or combustion arch, and f is the boiler up-take.

g, g^x represents the two part air-heater arrangement in which the incoming air for supporting combustion is pre-heated in the manner above referred to, by the heat of the waste gases on their way to the funnel or uptake f . g is the preliminary heater, and g^x the final heater.

Each heater section g, g^x is of the tubular or any other convenient type and the part g^x is placed as close to the furnace as possible, so as to receive the waste gases in their hot-test state immediately they leave the heating surface.

g^1 represents the economizer for heating the feed water which is placed between them, and serves to separate the two heater sections g, g^x .

In the example shown this economizer comprises a hot-air casing containing a nest of water-tubes having inlet and outlet pipes such as g^2, g^3 .

The upper or preliminary heater or section g receives all the incoming air and raises its temperature, such air entering by a rear opening in the middle of the heater and flowing to the right and left as indicated by the arrows 1. The lower and hotter or final heater 70 or section g^x , viz the one nearer to the furnace, receives at each end a portion of this air from the other section in the known manner and gives it the extra heat.

This extra-heated air is then led from an opening j^1 at the middle of the extra heater g^x (according to the type of boiler or furnace) by any convenient arrangement of passages or ducts h (with regulating valves or dampers) into the top of the furnace, viz 80 above the chain grate b .

In the example shown the ducts h communicate with the ends of a transverse air passage i arranged above the arch e , suitable vents i^1 being provided in the latter, so that 85 the extra-hot air from the final heater g^x mingles with the gases and volatile matters given off by the fuel and throws them into intense combustion, but this occurs well away from the grate itself, and without contributing to risk of injury to the latter.

The relative quantity of extra-heated air going to the furnace varies with the class of fuel, and may be so much as one half of the whole for highly volatile fuels, suitable 95 dampers such as h^x being provided where necessary to regulate the proportion of the two kinds of air.

The less-highly heated air from the upper or preliminary section of the heater, viz the portion which is not passed through the lower or super-heating section, is led by separate pipes or channels h^1 to the space below the grate, where of course it passes between the bars to start the combustion of the fuel 105 in the usual way. Owing however to this air being at a lower temperature than it would be if it had also passed through the whole of the air-heater, it tends in fact to keep the temperature of the bars themselves 110 lower even than it would be with an ordinary air-heating system.

As regards the arrows in the drawing, 1 shows the direction of the cold in-coming air; 2, 2 show the paths of the less-heated air to the furnace and 3, 3 the divided path for 5 that portion which goes into the hottest part of the heater, whence it passes (as the hotter air) by the path 4—4 into the top of the furnace, which it enters as at 5—5.

The arrows 6 show the paths of the flame 10 and hot gases from the furnace to the heater 7 whilst 7 shows the path from the latter into the uptake.

In this way, an increased temperature is obtained in the combustion zone of the furnace owing to the superheat of the top air supply giving a correspondingly increased steaming power and efficiency of the boiler, whilst the wear and tear on the grate is less than it would be with an ordinary pre-heated air supply.

Moreover the ordinary combustion arch or radiator *e* such as common with automatic stokers, can be very much reduced in size or dispensed with altogether, and thus the heat 25 which it usually intercepts is allowed to reach the heating surface of the boiler by direct radiation, adding further to the efficiency and steaming power.

The combustion of the volatile distillates 30 and of the carbon monoxide and other products of primary combustion, rising from the fuel, is thus promoted in the furnace itself,

namely well above the grate and therefore out of contact with the latter. The combustion which takes place on the grate itself is mainly 35 that of the fixed carbon in the fuel, and the temperature generated in the fuel bed is reduced on this account, being still further lowered owing to the air from the ash-pit being cooler than if the whole air supply were 40 uniformly heated. Hence the risk of burning and damaging the grate is materially reduced.

The invention is furthermore particularly applicable to grates of the compartment type, 45 or those in which the pressure of the air under the grate is graduated to suit the diminishing thickness of the fuel bed towards the back of the grate.

I claim:—

In a steam boiler provided with a flue for waste gases and a furnace having a grate, the combination with said flue of a final air heater, an economizer and a preliminary air heater disposed therein and arranged to be 55 traversed by the gases in the order named, means for conducting part of the air heated in the preliminary heater therefrom to a point below said grate, and means for conducting the rest of the heated air from said 60 preliminary heater through said final heater to a point above said grate.

In testimony whereof I affix my signature.

WILLIAM HENRY OWEN.
